STEAM HEATING SYSTEM

Filed July 22, 1919

Patented Aug. 12, 1924.

1,504,958

UNITED STATES PATENT OFFICE.

JAMES J. LAWLER, OF PELHAM, NEW YORK.

STEAM-HEATING SYSTEM.

Application filed July 22, 1919. Serial No. 312,485.

To all whom it may concern:

Be it known that I, JAMES J. LAWLER, a citizen of the United States of America, residing at Pelham, in the county of West- 5 chester and State of New York, have invented certain new and useful Improvements in Steam-Heating Systems, of which the following is a specification.

The primary object of the present invention resides in the provision of a steam heating system wherein the steam conduits of the system are normally open to the atmosphere and are adapted to be closed by thermostatically controlled devices operated 10 by steam passing through the conduit initially to eliminate all air from the conduit to permit an unrestricted circulation of steam therethrough.

A further object of the invention includes 20 in a steam heating system, which is thermostatically closed to the atmosphere, means for returning steam condensation to the boiler that is automatic in its operation and wherein the condensation is elevated to a 25 point above the upper end of the boiler and having a steam and water separating device associated with the upper end of the condensation returning means with a return pipe positioned between the boiler and 30 the separating or condensing tank.

A still further object of the invention is to provide in a steam heating system, means for returning the condensation of steam to the boiler and wherein the returning mechanism 35 is automatic in its operation so that the operation of the device is practically continuous and uninterrupted, the condensation being automatically returned to the boiler and operating a return check valve 40 controlling entrance to the boiler by hydrostatic pressure.

With the above general objects in view and others that will appear as the nature of the invention is better understood, the 45 same consists of the novel construction, combination and arrangement of parts to be hereinafter described in detail and then specifically claimed.

One embodiment of the invention is shown 50 in the accompanying drawing which illustrates a side elevational view with parts thereof shown in section of a boiler, heating elements associated therewith and return conduits for the condensation of steam.

Briefly described, the present invention 55 aims to provide an improved steam heating

system that is entirely automatic in its operation after a sufficient quantity of water has been placed in the boiler and the heating element is in operation, it being understood that any preferred type of heating element or elements may be employed with the boiler, there being shown a jacketed steam kettle, a glue heater and a steam heated cylinder. A main steam supply pipe 60 forming communication between the boiler and the several heating elements with branch pipes extending therefrom in direct communication with the heating element while drain pipes extend from the heating element to a return pipe section that will herein be termed a "riser." A thermostatically controlled trap is associated with the lower end of the riser and a separating or condensing tank is connected to the upper end 65 thereof, a return pipe for the condensation of steam extending from the condensation tank to a point adjacent the lower end of the boiler and preferably to the inner side of the controlling valve of the water supply pipe, while a check valve is interposed between the connection and the steam generator and is automatic in operation to permit the condensation to flow from the return pipe to the boiler by hydrostatic 70 pressure thereof created in the return pipe.

Describing the invention more fully in detail, the reference numeral 1 designates a steam boiler of any desired type, one that may employ coal or liquid fuel as the heating medium, the same being provided with an ordinary form of water gage 2, a steam release valve 3 and a hand valve 4, the latter valve being in communication with the steam chamber of the boiler 1 by the pipe 5. 75

Steam generated in the boiler passes through the pipe 5 into the main delivery pipe 6, the passage of which is controlled by the hand operated valve 7 while a plurality of branch pipes 8, 9 and 10 extend from the delivery pipe 6 to heating elements 11, 12 and 13, the passage of steam through the branch pipes 8 to 10 being controlled by the hand operated valves 14, 15 and 16 and the pipes 8 to 10 respectively. 80

The heating elements may be in the form of any device that it may be desired to heat by steam, conventional forms being shown, such as a steam jacketed kettle 11, a pair of glue pots 12 and a steam heated cylinder 13; but it is to be understood that any other form of heating element may be substituted 85

therefor as the type of heating element does not enter into the specific invention.

The steam heated elements 11, 12 and 13 are attached respectively to branch drain pipes 17, 18 and 19 that communicate with the main line return body which connects the lower end of the riser 21. A valve 22 controlled in its operation by any type of thermostat desired, such as is indicated by the numeral 23 has a pipe connection 24 with the lower end of the riser 21, the purposes of which will presently appear. The upper end of the riser 21 extends to a horizontal plane above the boiler 1 and carries at its upper end the horizontal branch pipe 25 in communication with the upper end of the water and steam condensing tank 26, a vent pipe 27 extending outwardly of the upper end of the condensing tank 26 and having a valve 28 thermostatically controlled as at 29, while the outlet in the tank communicating with the pipe 27 is adapted to be closed by a valve on the stem 30 operated by a system of levers including a pair of depending brackets *d* and *e* and a lever *f* pivoted to the bracket *e* and carrying a float 32. A link *g* connects the lever *f* to one end of the link *h* carried by the bracket *d* and to which link the valve stem is attached. A return pipe 33 extends from the lower wall of the condensing tank 26 on the main water supply pipe 34 and is connected thereto to the boiler side of the valve 35, a check valve 36 being provided in said connection between the pipe 33 and the boiler 1 to permit the condensation in the pipe 33 to flow past the same and into the boiler, and to prevent a back-flow of the water from the boiler.

With the structural details specifically described, and it being desired to cause the passage and circulation of steam to the heating elements 11, 12 and 13, it being understood that the valve 22 controlling the exhaust of the steam from the system and the valve 28 exhausting to the air, are open with the surfaces of the heating element, valves and pipes being cold, steam formed in the boiler 1 will pass through the pipe 5 into the main supply pipe 6 with the valve 7 open and into the branches 8, 9 and 10 and by way of the valves 14, 15 and 16 to the heating elements and from the heating elements to the drains 17, 18 and 19 to the main return pipe 20. The steam principally exhausts through the pipe 24 by way of the valve 22 while air escapes through the riser 21, branch 25, condensing tank 26 and outer pipe 27 by way of the valve 28 to the atmosphere. Steam continues to escape, clearing the system of all air until the parts are sufficiently heated to cause an operation of the thermostats 23 and 29 for automatically closing the valves 22 and 28 thus locking the steam heating system against the atmos-

sphere and preventing the entrance of air thereto. After the steam passes through the thermostat 23 operating to close the valve 22, water of condensation lying in the pipe 24 and thermostat 22 will contain sufficient heat, due to the passage of steam through the system, to retain the valve 22 closed. Also, steam condensing in the tank 26 will have heated vapors or light steam arising therefrom to cause the thermostat 29 to close the valve 28.

With the steam heating system in full operation, steam will pass through the pipe sections to the heating elements and heat radiated through said elements will cause a partial condensation of the steam, the same draining from the heaters through branch pipes 17, 18 and 19 into the main return line 20 and the condensation together with steam will fill the pipe 24 as far as the valve 22 and will then be elevated in the riser 21 substantially in the manner as illustrated, the water of condensation being in the form of small bodies or slugs *a* separated by steam bubbles or slugs *b* to the horizontal pipe 25 for entry into the condensing tank 26 whereupon water of condensation will flow from said condensing tank into the return pipe 33 and partially fill the same as indicated by the reference character *c*. The column of water in the return pipe *c* is supported at a certain height by the boiler pressure on the check valve 36, but due to the elevation of the water of condensation in the riser 21 and hydrostatic pressure in the return pipe 33, the pressure in the boiler 1 upon the check valve 36 is overcome and the water of condensation permitted to flow past said check valve and into the boiler thus causing a continuous return circuit for the water of condensation coming from the heating elements. With the natural operation of the steam heating system, the float 32 and valve 30 remain functionless, the steam passing upwardly of the riser 21 filling the tank 26 and pipe 27 as far as the valve 28, but should the check valve 36 prove to be faulty and permit a leakage by back pressure in the boiler, the rise of water in the pipe *c* would elevate the float 32 and through the system of levers 31 close the valve 30 upon its seat so that water would not flow outwardly thereof to chill the valve 28 and cause the thermostat therefor to open same. The water in the pipe 24 is practically maintained at sufficient temperature to cause the thermostat to retain the valve 22 in closed position by being disposed in proximity of the return pipe 20, but should the water in said pipe effect the opening of the valve, the immediate introduction into said pipe of steam and hot water will quickly close the drain with the restoration of a complete circuit for the steam and condensation.

From the above detailed description of the construction and operation of the invention, it will be understood that the gist thereof resides principally in the elevation 5 of the condensation of steam to the condensing tank with a return pipe from the condensing tank to the boiler, the upper end of the riser and condensing tank being spaced above the boiler to create hydrostatic pressure 10 sure in the return pipe for an automatic operation of the check valve controlling the return entrance to the boiler. It is to be understood that any preferred form of valve may be substituted for the ones illustrated 15 by the reference numerals 22 and 28 as well as a replacement by an efficient thermostatic device to be used in lieu of the ones herein illustrated. The specific form of heating elements does not enter into the invention, conventional forms being shown while the valve 20 for controlling the outlet to the separating tank 26 may be readily substituted by another one. The column of water in the boiler 1 may be increased by opening the 25 valve 35 in the supply pipe 34 to permit a flow of water past the check valve 36 into the boiler.

What I claim as new is:—

1. Means for effecting a flow of steam 30 condensation comprising a steam generator,

heating elements in communication therewith, a riser for condensation, a thermostatically controlled exhaust associated with the lower end of the riser, and a return pipe in communication with the upper end of 35 the riser.

2. Means for effecting a flow of steam condensation comprising a steam generator, 40 heating elements in communication therewith, a riser for condensation, a thermostatically controlled exhaust associated with the lower end of the riser, a thermostatically controlled valve associated with the upper end of the riser, and a return pipe in communication with the upper end of the riser. 45

3. Means for effecting a flow of steam condensation comprising a steam generator, 50 heating elements in communication therewith, means for returning condensation to the generator comprising a riser, a thermostatically controlled exhaust associated with the lower end of the riser, a separating tank for steam and water adjacent the upper end thereof, a hydrostatic pressure pipe between the tank and generator, and a check 55 valve positioned between the hydrostatic pressure pipe and the generator.

In testimony whereof I affix my signature.

JAMES J. LAWLER.
